FIRE STARTER NOZZLE

Leslie G. Boyd, Dallas, Tex., assignor of fractional part
interest to Daniel B. Jackson, Seymour, Tex.

Filed Aug. 21, 1973, Ser. No. 390,326

Term of patent 14 years

Int. Cl. D23—05

U.S. Cl. D23—90.1

FIG. 1

FIG. 2

FIG. 1 is a top front left perspective view of a fire starter nozzle in accordance with my new design; and

FIG. 2 illustrates a bottom rear right perspective view of the invention illustrated in FIG. 1.

I claim:

The ornamental design for a fire starter nozzle, substantially as shown.
